DESIGN.

—o—

A. ROSENSTEIN.

CANE OR UMBRELLA HANDLE.

No. 20,148.

Patented Sept. 9, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,148, dated September 9, 1890.

Application filed July 31, 1890. Serial No. 360,576. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to which it pertains to make and use it, reference being had to the accompanying drawing, which forms part of this specification.

My invention relates to an improvement in designs for cane, umbrella, or parasol handles; and it consists in the ornamental shape and configuration of parts whereby a novel, pleasing, and beautiful effect is produced, as will be more fully described hereinafter.

The accompanying photographic illustration represents my invention.

A represents the straight or main portion of the handle, and which has its outer end curved or bent, so as to form a ring or circle B. Near the inner end of this part A is formed an ornament C, of any suitable description, and climbing up around this part A is the figure of a naked infant D, one foot of which rests upon a portion of the ornament C. Sitting in the ring or circle B and holding on with one hand, which is extended backward, is a second infant F, and just above the one F is a third child or infant G, which is holding on to the handle with both

arms and feet. Both at the junction of the ring or circle and at different places upon its sides are any suitable ornamentations. As will be seen, the three figures of the infants are arranged one above the other and have the appearance of climbing upon the handle as if in play.

The handle constructed as here shown and described presents a very pleasing effect and adds greatly to the appearance of the article to which the handle is to be applied.

While I here show an infant upon the vertical portion of the handle and two infants clinging to the ring, I do not limit myself to this exact arrangement, as it will be readily seen that the infants clinging to the ring may be omitted without impairing the rest of the design, or the infant upon the vertical portion omitted without impairing the other part of the design; so, also, there may in either case be only one infant clinging to the ring, if desired.

Having thus described my invention, I claim—

A design for a cane, parasol, or umbrella handle, substantially as herein shown and described.

In testimony whereof I affix my signature in presence of two witnesses.

ALBERT ROSENSTEIN.

Witnesses:

E. P. ELLIS,

ALLEN S. PATTISON.
